UNITED STATES PATENT OFFICE.

BURTNETT McINTOSH, OF NEW YORK, N. Y., ASSIGNOR TO FRANK A. HALL, OF NEW YORK, N. Y.

CLIP.

No. 907,270.

Specification of Letters Patent.

Patented Dec. 22, 1908.

Application filed February 20, 1908. Serial No. 416,860.

To all whom it may concern:

Be it known that I, BURTNETT McINTOSH, of the city of New York, borough of Brooklyn, county of Kings, and State of New York, have invented certain new and useful Improvements in Clips, of which the following is a full, clear, and exact specification, such as will enable others skilled in the art to which it appertains to make and use the same.

My invention relates to a clip especially intended for fastening ratan binding strips to mattress springs. It is customary to employ ratan strips extending around the margin of such springs to furnish a corner or edge over which the canvas covering is drawn, and great difficulty has heretofore been experienced in securing a sufficiently simple and cheap device which will, nevertheless, hold securely the ratan of varying diameter.

The principal feature of my invention, therefore is to provide an efficient device for this purpose and to this end my invention resides in certain special features of construction and arrangement of parts which will be fully set forth hereinafter and particularly pointed out in the claims.

My invention involves various other features of importance and all will be fully set forth hereinafter and particularly pointed out in the claims.

Reference is had to the accompanying drawings, which illustrate, as an example, one manner of embodying the principles of my invention, in which drawings,

Figure 1 is a plan view showing a fragment of the spring and a fragment of the ratan joined by my improved clip; Fig. 2 is an enlarged section on the line 2—2 of Fig. 1; Fig. 3 is a detail perspective of the saddle; and Fig. 4 is a detail of a tool which may be employed to fasten the clip.

The clip is preferably constructed of metal and is composed of two parts, a saddle A and a strap B. The saddle has a curved seat a with which the ratan C is engaged. The edge a' of this seat is slightly sharpened so that it will indent or slightly enter the ratan as will hereinafter fully appear. The saddle further comprises a bend a^2 adapted to receive the top convolution d of the spring D. In this bend is formed an opening a^3 to receive the strap as will hereinafter be fully set forth. From the bend a^2 the body of the saddle extends downward

and inward and terminates in a bend a^3 engaging the second convolution d' of the spring D. The strap B has its end b entered into the opening a^3 of the saddle, turned around the convolution d of the spring and passed back between the ratan and the body of the strap, the pressure of the body of the strap against this end holding the same firmly in place. The strap is then passed around the ratan and downward past the saddle A through the opening a^3 first in the position indicated by the broken lines in Fig. 2. A suitable tool, such for instance as the instrument shown in Fig. 4, with a slot X in its end is then engaged with the end of the strap in the slot X. Then the tool is rotated to coil up the end of the strap in a coil indicated at b' such coil lying against the underside of the body of the saddle and rotation of the tool being continued until sufficient pressure is brought to bear on the strap. The strap is thus strained around the ratan and imparts to it a slightly rotating motion in the direction of the arrow shown in Fig. 2, causing the sharp end a' of the saddle to make an impression into the ratan, thus rigidly and most securely connecting the saddle and ratan with the upper convolution d of the spring. The strap is formed of suitable metal such, for instance, as hoop iron and has sufficient stiffness to cause the coil b' to retain its form. The coil, therefore, presses against the body of the saddle and prevents relaxation of the tension of the strap.

It will be seen that the device is arranged to be readily applied. By connecting the saddle with the second convolution d' of the spring or with some other part of the spring, the saddle is prevented from rotating on the convolution d and I am thereby permitted to exert the necessary strain on the strap. This strain on the strap not only firmly holds the ratan in the seat of the saddle, but it also draws the top convolution d of the spring up firmly into the bend a^2 of the saddle thus making an absolutely rigid structure. Not only does the improved clip firmly hold the ratan in place, and permit instant application, but it readily and completely adapts itself to ratan of varying diameter a result which has not, to my knowledge, been heretofore attained by a device which may be cheaply constructed and easily and effectually applied.

Having thus described the preferred embodiments of my invention, what I claim as new and desire to secure by Letters Patent of the United States, is—

- 5 1. A clip for the purpose specified comprising a saddle adapted to engage the spring at two points and a strap adapted to encircle the ratan, one end of the strap engaging the spring and the other end engaging the saddle. 55
- 10 2. A clip for the purpose specified having a saddle having a seat to be engaged by the ratan and a bend to receive a convolution of the spring and a strap engaged at one end 60 with said convolution of the spring and passed around the ratan, the other end of the strap engaging the saddle.
- 15 3. A clip for the purpose specified comprising a saddle adapted to be engaged by the ratan and a strap for holding the ratan in place, one end of the strap being turned into a coil, whereby tension may be exerted on the strap. 65
- 20 4. A clip for the purpose specified comprising a saddle adapted to be engaged by the ratan and a strap for holding the ratan in place, one end of the strap being turned into a coil, whereby tension may be exerted on the strap, said coil engaging the saddle 70 and retained thereby.
- 25 5. A clip for the purpose specified comprising a saddle adapted to engage the spring and having a bend to receive a convolution of the spring, the saddle having an opening at said bend and a seat beyond the same, the seat receiving the ratan and a strap one end of which is passed through the opening in the saddle and engaged with 75 said convolution of the spring, the strap passing around the ratan its other end projecting through said opening in the saddle and turned in a coil against the saddle. 80
- 30 6. A clip for the purpose specified, comprising a saddle having a bend intermediate its ends receiving the top convolution of the 85 spring, means for connecting one end of the saddle with the second convolution of the spring, a seat formed at the other end of the saddle with which seat a ratan is engaged and a strap having one end engaged with the first named convolution of the spring the strap turned around the ratan and its other end projected through an opening in the saddle and being coiled against the same for the purpose specified. 90
- 35 7. A clip comprising a saddle adapted to engage the spring and a strap adapted to encircle the ratan, one end of the strap engaging the spring and the other end engaging the saddle. 95
- 40 8. A clip comprising a saddle having a seat to engage the ratan and a pliable metal strap adapted to encircle the ratan, one end of which strap is fastened immovably with respect to the saddle and the other end of which is coiled against the saddle whereby tension may be exerted on the strap to hold the saddle in place. 100
- 45 9. A clip comprising a saddle having a seat to engage the ratan and a pliable metal strap adapted to encircle the ratan, one end of which strap is fastened immovably with respect to the saddle and the other end of which is coiled against the saddle whereby tension may be exerted on the strap to hold the saddle in place, the saddle having a sharp edge adapted to impinge the ratan to prevent the saddle from moving under the tension of the strap. 105
- 50 10. A clip comprising a saddle having a seat to engage the ratan and also having a portion fastened to the spring and a pliable metal strap one end of which is fastened immovably with respect to the saddle and spring, the strap encircling the ratan and having its other end coiled against the saddle, whereby the strap may be placed under tension to hold the saddle in place. 110
